DOMESTIC WATER SYSTEM

Filed April 17, 1936

UNITED STATES PATENT OFFICE

2,100,109

DOMESTIC WATER SYSTEM

William H. Ryan, Newburgh, N. Y.

Application April 17, 1936, Serial No. 74,839

3 Claims. (Cl. 103—6)

This invention relates to domestic water systems, and more particularly to a means for supplying fresh air to the storage tank incorporated in the system.

5 An object of this invention is to provide an improved means whereby air may be regularly and automatically supplied to the storage tank of a domestic water system.

Another object of this invention is to provide 10 a means whereby at least a portion of the discharge pipe of the pump may be drained of water when the pump or supply means for the storage tank has been cut off, and air admitted into the emptied portion of the system, the means for 15 admitting air into the system being cut off coincidentally with the starting up of the pump.

A further object of this invention is to provide 20 an improved draining and air supplying means which is so constructed as to prevent the pocketing of air in the system so that the incoming air will be forced into the storage tank each time the pump connected to the tank is set in operation.

With the foregoing and other objects in view, 25 the invention will be more fully described hereinafter, and will be more particularly pointed out in the claims appended hereto.

In the drawing, wherein like symbols refer to like or corresponding parts throughout the several views:

30 Figure 1 is a detail side elevation, partly broken away and in section, and partly diagrammatic, of a means for supplying air to a water system.

Figure 2 is a fragmentary sectional view taken on the line 2—2 of Fig. 1.

35 Figure 3 is an enlarged fragmentary vertical sectional view of the air valve.

Referring to the drawing, the numeral 10 designates a water pump of conventional construction, and here shown as a rotary pump, which is connected to a suitable source of power supply in the 40 form of a motor 11. The intake side 13 of the pump 10 is adapted to be connected to a suitable source of water supply, such as a well or water reservoir, and the outlet side 12 is adapted to 45 be connected as by branches 14, 15 and 16 to a water tank (not shown).

The motor 11 is connected as by conductors 17 and 18 to a suitable source of electric current supply, the electric circuit being shown diagrammatically in Fig. 1.

In order to provide a means whereby air may be automatically and periodically supplied to the water system between the tank and the pump 10, I have provided a drum or enlarged casing 19 which is interposed in the branch pipe 16, and

this casing 19 is provided at the intake end with a cap 20 having a nipple 21 disposed adjacent the bottom thereof, the nipple 21 being connected to the branch 16. The other or outlet end of the casing 19 is provided with a second cap 22 having 5 a nipple 23 disposed adjacent the top thereof, the nipple 23 being connected to a branch pipe 16a. The branch pipe 16a leads to the tank (not shown) and intermediate the tank and this branch pipe 16a, a suitable check valve is provided such as is 10 ordinarily used to prevent the return of water from the storage tank. When the pump 10 is stopped, the water in the casing 19 is drained by means of a drain pipe 24 which is connected to the lower portion of the casing 19. The drain 15 pipe 24 has branches 25 and 26 connected thereto, the branch 26 being connected to a suitable carry-off means. If desired, the branch 26 can be connected with the pipe 13, and the water again taken into the system and thereby re-used. 20

In order to facilitate the draining of the water from the casing 19, an air vent pipe 27 is connected at one end to the top of the casing 19, and the other end of the pipe 27 is provided with a spring-pressed valve member 28, the spring 29 25 of which normally urges the valve 30 to closed position. A valve stem 31 is connected to the valve member 30 and extends upwardly for engagement by a vertically movable valve operating arm 32. The arm 32 is secured to a vertically 30 slideable rod 33, and is adjusted by means of a set screw 34. The rod 33 slides through a guide 35 carried by a stationary arm 36 which is clamped or otherwise secured to a supporting rod 37. The rod 37 is disposed in a vertical position, and has 35 the lower end thereof mounted in a connection 38 which is interposed in the pipe 25, the connection 38 being in this instance a T-coupling member with the rod 37 mounted in and closing one branch thereof. 40

A solenoid 39 is secured as by a mounting means 40 to the upper end of the supporting rod 37, and the solenoid 39 is connected as by conductors 41 and 42 to the conductors 17 and 18, respectively, so that when the motor 11 is in operation electric 45 current will also flow through the conductors to the solenoid 39. A movable core 43 is secured to the upper end of the rod 33 so that when the solenoid 39 is energized the core 43 will be drawn upwardly, and as the arm 32 is connected to the 50 slide 33, which has the core 43 on the upper end thereof, upward movement of the solenoid core 43 will release the arm 32 from the valve stem 31 and permit the spring 29 to cut off the entrance of air into the pipe 27 by closing the valve 30. 55

A drain valve member, generally designated as 44 is interposed in the pipe 25, and comprises a casing 45 having a valve member 46 disposed therein and provided with a valve stem 47. A 5 spring 48 normally urges the valve member 46 to closed position. A second stem 49 is secured to the valve member 46 and extends outwardly of the housing 45 through a gland 50. A valve opening rock lever 51 is pivoted on an arm 52 10 carried by the housing 45, and one end of the lever 51 engages the extended end of the stem 49. The other end of the lever 51 is disposed between the arms of a yoke 53, being pivotally secured between the arms of the yoke 53 by means of a pivot 15 54. The yoke 53 is secured to the lower end of the slide rod 33, and the arms of the yoke 53 engage on opposite sides of the pipe 25. A weight 55 is secured to the operating member or rod 33 above the guide 35 and offsets the tension of the 20 spring 48, so that when the current to the motor 11 is cut off, and likewise the current to the solenoid 39 is cut off, this weight 55 will gravitatingly move the rod 33 downwardly so as to open the air valve 28 and simultaneously rock the lever 51 to 25 thereby open the valve member 46.

The hereinbefore described device is operated in the following manner: When the motor 11 is energized by closing the circuit embracing the conductors 17 and 18, the pump 10 will force 30 water upwardly through the pipes 14, 15, 16 and 16a into the tank connected to the pipe 16a. Assuming that the motor 11 is shut off, then the solenoid 39 will be de-energized, and the weight 35 55 will move the operating rod 33 downwardly and carry therewith the air valve operating arm 32, which will open the air valve 28, and at the same time, the lever 51 will move the valve member 46 to open position against the tension of the spring 48. The water in the drum or casing 19 will then drain out through the drain pipes 24, 40 25 and 26, through the valve 44.

As soon as the motor 11 is energized and set in operation, and the pump 10 likewise operated, the electric current will also flow through the conductors 41 and 42 so as to energize the solenoid 39. When the solenoid 39 is energized, the core 43 will be drawn upwardly, and movement of the core 43 upwardly, will move the arm 32 to released position and also rock the lever 51 to released position. The spring 29 will close the 45 50 valve 30 and thereby prevent the entrance of any air into the drum or casing 19 through the pipe 27, and the spring 48 will close the valve 46 so that water will be prevented from draining through the pipes 24, 25 and 26.

55 In view of the fact that the incoming water which enters the casing 19 is taken in through the nipple 21 near the bottom of the casing, the air in the casing 19 will be forced upwardly and will be discharged into the pipe 16a by reason of 60 the fact that the outlet for the casing 19, namely, the nipple 22 which is at the top thereof and opposite from the inlet. This action of the air takes place during the operation of the pump, the pipes 27 and 24 being then closed.

65 It will be apparent from the foregoing that each time the motor 11 is operated there will be a quantity of air forced into the pressure tank so that a constant supply of fresh air will be supplied the water tank, the quantity of air being 70 determined by the size of the drum or casing 19 which may be varied to suit the needs of the particular tank.

The tank 60, as is well known, has connection with a pipe 16a which in turn makes connection with the casing 19, as shown in Fig. 1.

Well known electrical connections in the form of conductors 61 and 62 may be connected to the tank 60, said conductors 61 and 62 being in turn connected with the motor 11. A float signal 63 in the tank 60, closes the electrical circuit of the 5 conductors and thereby the motor 11 is actuated, all in a manner well known. The novelty, however, consists in a means for automatically supplying air to a water system having a pump operated by an electric motor for supplying water to a 10 pressure tank, and having a pipe for conducting water to the tank, a check valve in said pipe, the combination of a horizontally disposed casing adapted for the passage of the pumped water therethrough and disposed in the pipe line between the check valve and pump, a drain pipe communicating with the casing and connected with the lowermost part thereof, a valve in said drain pipe, a solenoid in circuit with the motor, an armature raised against the action of gravity 15 by the solenoid, a rod connecting the armature with the valve, and a weight on said rod for causing the rod to descend under the action of gravity whereby upon the lowering of the rod by the action of gravity, upon the stoppage of the pump 20 and non-actuation of the solenoid the water is drained by the drain pipe from the casing, and upon the raising of the armature by the solenoid, the valve is closed and the draining of water by the pipe from the casing is prevented and the 25 water and the air in the pipe is forced into the tank when the pump is in operation and the solenoid actuated.

It will have been noted that the purpose of the invention as embodied in the device shown is to 30 furnish air to the storage tank of domestic water systems, at a predetermined rate, regularly and automatically, and by so doing, to take the place of present air cylinders, air compressors and similar devices.

It is of course understood that various changes and modifications may be made in the details of the above specifically described embodiment of this invention, such changes and modifications being limited only by the scope of the appended 45 claims.

What is claimed is:

1. A means for automatically supplying air to a water system having an electrically operated pump, comprising a casing adapted to be interposed in the system on the outlet side of the 50 pump, an air intake means connected to the casing, a drain pipe connected to the casing, a spring pressed valve in the air intake means, a spring pressed valve in the drain pipe, means engaging each of said valves for moving said valves to open position when the pump is inoperative, and means engaging said latter means for disengaging said latter means from the valves when the 55 pump is operative.

2. A means for automatically supplying air to a water system having a pump operated by an electric motor, comprising a casing adapted to be interposed in the system on the outlet side of the pump, air vent means for said casing, a drain pipe connected to the casing, spring-pressed and normally closed valves in said air vent means and said drain pipe, a vertically slid able rod, guide means for said rod, an arm carried by the rod and disposed in the path of the air vent valve, 60 a pivoted lever secured to the rod and engaging the drain valve, a weight secured to the rod and gravitatingly urging said rod downwardly whereby to open each of said valves, a solenoid in circuit with the motor, and a movable core secured 65 to the rod, the weight being disposed to urge the 70 rod downwardly when the solenoid is de-energized and the weight being disposed to urge the rod upwardly when the solenoid is energized, the weight being disposed to urge the rod downwardly when the 75 pump is inoperative and the weight being disposed to urge the rod upwardly when the pump is in operation.

to said rod and adapted upon energization of said solenoid to move said rod upwardly and thereby move said arm and said lever to released position.

3. In a means for automatically supplying air to a water system having a pump operated by an electric motor for supplying water to a pressure tank, and having a pipe for conducting water to the tank, a check valve in said pipe, the combination of a horizontally disposed casing adapted for the passage of the pumped water therethrough and disposed in the pipe line between the check valve and pump, a drain pipe communicating with the casing and connected with the lowermost part thereof, a valve in said drain pipe, a solenoid in circuit with the motor, an armature

raised against the action of gravity by the solenoid, a rod connecting the armature with the valve, and a weight on said rod for causing the rod to descend under the action of gravity whereby upon the lowering of the rod by the action of gravity, upon the stoppage of the pump and non-actuation of the solenoid the water is drained by the drain pipe from the casing, and upon the raising of the armature by the solenoid, the valve is closed and the draining of water by the drain pipe from the casing is prevented and the water and the air in the pipe is forced into the tank when the pump is in operation and the solenoid actuated.

WILLIAM H. RYAN. 15
